WELL SHUTOFF DEVICE

Will E. Boyd, Houston, Tex., assignor to Gulf Oil Corporation, Pittsburgh, Pa., a corporation of Pennsylvania

Application October 29, 1954, Serial No. 465,696

11 Claims. (Cl. 166—63)

This invention relates to a device positioned down the hole of a well for shutting off production from the well, and in its preferred embodiment to a shutoff device for substantially simultaneously shutting down production from both zones of a dual zone well.

It is frequently desirable to shut down an oil well when a hazardous or potentially hazardous condition exists at the well head. A device which will automatically shut down the well is particularly desirable for use in off-shore wells. Often a number of off-shore wells are drilled from the same platform, and a hazardous condition in one well may endanger production from the other wells. Moreover, off-shore wells are exposed to a number of hazards, such as vessels colliding with the wells, or high waves, to which on-shore wells are not exposed. If the hazardous condition at the off-shore well is the result of a storm, the well may not be accessible while operation of the well is endangered and, hence, it is desirable to have a device to shut down the well, which will act automatically in response to a signal initiated by the hazardous condition.

This invention resides in a device positioned down the hole of an oil or gas well for shutting down the well when a hazardous or potentially hazardous condition exists at the well head or within the well. The device is actuated by an explosive charge positioned in the shutoff device which severs means holding valve elements within the device in an open position. In a preferred embodiment of this invention, the device simultaneously shuts down production from both zones of a dual zone well.

In the drawings, Figure 1 is a fragmentary diagrammatic longitudinal sectional view of a dual zone well equipped with the shutoff device of this invention showing conventional well head connections.

Figure 2 is a longitudinal sectional view of the shutoff device of this invention in an open position permitting production from both zones of the well.

Figure 3 is a longitudinal sectional view of the shutoff device illustrated in Figure 2 in the closed position.

Figure 4 is a fragmentary longitudinal sectional view of the lower end of another embodiment of this invention of the shutoff device in the closed position.

In Figure 1 of the drawings a dual zone well equipped with the shutoff device of this invention is schematically illustrated having a surface casing 10 supported in a casing head hanger 12. The surface casing 10 extends downwardly into the well for a distance determined by the usual considerations in drilling, and is not limited by this invention. The surface casing 10 will ordinarily be surrounded by a conductor pipe, not shown, in off-shore installations. A production casing 14 extends downwardly into the well, within the surface casing 10, to a position at least immediately above the upper production zone of the well. In the well illustrated in Figure 1 of the drawings, the production casing 14 extends to the bottom of the well and is perforated at 16 and 18 to permit flow from the upper and lower producing zones

2

of the well, respectively. A casing hanger 20 mounted at the upper end of the casing head hanger 12, supports the production casing 14 within the borehole.

Conventional well head connections for control of the production of the well can be employed with the shutoff device of this invention, and have been illustrated in Figure 1. A casing head 22 resting upon the casing hanger 20 and secured to the casing head hanger 12 is provided with side outlets 24 and 26 for the discharge of production from the upper production zone. A tubing hanger 28 is supported within the casing head 22 at its upper end. Suspended from the tubing hanger 28 and extending down the hole to the lower production zone is a tubing string 30. A tubing head spool 32 mounted on the upper end of the casing head 22 is capped at its upper end and provided with a side outlet 34 for the discharge of production delivered through the tubing string 30 from the lower zone of the well.

Forming a part of the tubing string 30 is the shutoff device of this invention indicated generally by reference numeral 36, which divides the tubing string into an upper section above the shutoff device and a lower section below the shutoff device. The shutoff device can be located at any level in the tubing string above the upper production zone of the well, but is preferably near the top of the well and is ordinarily in the top 1000 feet of the hole. The lower section of tubing string 30 extends downwardly from the lower end of the shutoff device 36 through a packer 38 of conventional design set in place in the lower end of the casing 14 below the level of the upper production zone and preferably just above the lower production zone. Packer 38 is provided with a cap 40 at its lower end spring loaded toward the closed position. A perforated section 42 connected at the lower end of the tubing string 30 holds the cap 40 in the open position during normal operation.

Referring to Figure 2 of the drawings in which the shutoff device 36 is illustrated in detail, a head member 44 at the upper end of the shutoff device has a passage 45 extending through it. The passage 45 is threaded at its upper end for connection to the lower end of the upper section of the tubing string 30, and at its lower end for connection to a tubular mandrel 46.

The head member 44 is externally threaded at its lower end for connection with a shell 48. A number of ducts 50 extend lengthwise through the head member 44 for the transmission of annular production in the manner hereinafter described. An annular packer 52 secured to the outer surface of the head member 44 prevents flow of fluid between the head member 44 and casing 14.

The shell 48 is connected at its lower end to a mandrel housing 54 into which the lower end of the mandrel 46 extends. The lower end of the mandrel housing 54 is internally threaded at 56 for connection with the lower section of the tubing string 30.

A plurality of spaced rings 58 having central openings larger than the external diameter of the mandrel extend inwardly at intervals from the inner surface of the shell 48. A flapper valve 59 is mounted on the lower surface of each of the upper two rings in a position to move against the lower surface of those rings to close the central openings when the shutoff device of this invention is operated. A flapper valve 60 is mounted on the upper surface of the lowest ring 58 in position to swing downwardly against that ring. The flapper valves 59 and 60 are spring loaded toward the closed position. Any desired number of rings 58 and spring loaded flapper valves can be provided, and in the embodiment of the invention illustrated in Figure 2, three of each are employed. Moreover, all of the flapper valves may be mounted on the lower surface of the rings 58, for example,

when the shutoff device is to be used in a well in which the pressure of the lower producing zone is higher than the pressure on the upper producing zone. The shell 48 is perforated at 61 directly below the highest ring 58 to allow the flow from the upper zone of the well to enter the shell.

The tubular mandrel 46 extends downwardly from the lower end of the passage 45 in the head member 44 through the openings in the rings 58 beyond the lower end of the shell 48 and into the housing 54. Each of the flapper valves 59 and 60 is engaged by the mandrel 46 and held open to permit flow upward through the annular space between the rings and the outer surface of the mandrel. The tubular mandrel 46 passes through a packing gland 62 at the lower end of the shell 48 which prevents flow between the housing 54 and the shell 48. The lower end of the tubular mandrel is spaced above the lower end of the housing 54 during normal operation to permit downward movement of the mandrel when the shutoff device operates. A spring 64 compressed between a collar 66 on the lower end of the mandrel 46 and the lower surface of the packing gland 62 urges the mandrel downward toward the lower end of housing 54.

On a ring 58 above the perforations 61 is a charge of explosive 68. The explosive may be any of the conventional explosives of high brisance, typical examples of which are TNT, PETN, tetryl or cyclonite. It is preferred that the explosive charge 68 be in the form of a shaped charge in order to concentrate the force of the explosive against the tubing mandrel 46. A suitable detonator such as a conventional electrical blasting cap 70 is placed adjacent the explosive charge 68. The blasting cap 70 is connected with an electrical conductor 72 which extends upwardly through head member 44, for example by passing through one of the ducts 50, and continues upwardly through the space between the tubing string 30 and casing 14 to the well head. A suitable pressure-tight seal 74 is provided in the casing head 22 for carrying the conductor through the wall of the casing head.

The electrical conductor is connected at the surface to any suitable circuit for initiating the charge necessary to set off the detonator 70. The circuit may be actuated by any of a number of hazardous, or potentially hazardous, conditions against which it is desirable to protect the well. For example, a float-operated switch may be used to close the circuit to the detonator 70 in the event of high waves, or a pressure-actuated switch may close the circuit in the event of collision of some object with the platform. Protection against broken lines at the surface or in the well may also be obtained by suitable control mechanism actuated by loss of pressure in the lines. In the apparatus illustrated in Figure 1, the electrical conductor 72 is connected with a thermostat 76. When the temperature at the well head exceeds a predetermined limit, the thermostat 76 closes the circuit to a diagrammatically illustrated initiator 78 which sends a current to the blasting cap 70 which, in turn, sets off charge 68. Blasting cap 70 is grounded to complete the electrical circuit.

During normal operation of the well, flow from the lower producing zone enters the lower perforated section 42 of the tubing string 30 and passes upwardly through the tubing string 30 into the housing 54. The tubing flow then continues upwardly through the tubing mandrel 46 and the passage 45 in the head member 44 to the upper section of the tubing string 30. The tubing flow is discharged from the upper end of the tubing string into the head spool 32 and flows from the head spool to suitable collecting and control equipment, not shown. Production from the upper zone, referred to as the annulus flow, flows through the perforations 16 in the casing 14 and then through the annular space between the casing 14 and the tubing string 30 upwardly to the perforations 61 in the shell 48. The annulus flow then con-

tinues upwardly between the outer surface of the tubing mandrel 46 and the rings 58 into the ducts 50 and then upwardly into the casing head 22. The production from the upper zone is discharged through outlet 24 or 26, or both, to suitable control and collecting equipment, also not shown.

When a hazardous or potentially hazardous condition arises at the well head, or when it is desired to shut down the well for other reasons, the circuit through the electrical conductor 72 is closed, thereby setting off the detonator 70 which in turn sets off the explosive charge 68. In the apparatus illustrated in Figure 1, the circuit is closed by the thermostat 76 when the temperature at the well head exceeds a predetermined limit. The explosive charge cuts the tubing mandrel 46 which is then moved downwardly into the housing 54 by the compressed spring 64 to the position shown in Figure 3. As the upper end of the tubing mandrel 46 moves downwardly past the spring-loaded flapper valves 59 and 60, the valves move to the closed position illustrated in Figure 3, thereby preventing flow from the producing zones to the well head. In the embodiment illustrated in Figure 3 in which flapper valves 59 swing upward, and flapper valve 60 swings downward, to close, flow between the upper and lower producing zones is prevented, as well as flow from both of the producing zones to the well head.

The apparatus illustrated in Figures 2 and 3 of the drawings is adapted for use in dual zone wells. The shutoff device illustrated in those drawings can also be used in wells producing from a single zone.

In some instances, silt or sand carried by the oil by the lower producing zone may fill up the space in the housing 54 and interfere with operation of the shutoff device. The embodiment of the invention illustrated in Figure 4 of the drawings prevents such accumulation of silt or sand. The lower end of the mandrel 46 extends into a vertical sleeve 80 provided with a packing gland 82 at its upper end. The diameter of the sleeve 80 is only enough larger than the outer diameter of the mandrel 46 to permit the mandrel to slide in the sleeve, hence, it offers no opportunity for silt to build up in the sleeve. When the explosive charge is detonated and the mandrel severed, the lower end of the mandrel 46 is moved downwardly in the sleeve 80 by the spring 64 to the position illustrated in Figure 4.

This invention provides a positively actuated device for shutting off a well when continued operation of the well may be undesirable or endanger that well or other wells. The shutoff device may be connected to any of a wide variety of initiating devices to set off the explosive when any of many possibly hazardous conditions exist at the well head or in the well. The explosive charge has been illustrated as a ring surrounding the mandrel and supported on one of the rings 58, but the explosive charge may be of any shape and mounted in any position suitable for severing the mandrel at a point whereby movement of the mandrel by the spring will permit the flapper valves to move to the closed position.

What I claim is:

1. A shutoff device adapted to be arranged in the tubing string of a well comprising a shell, a head member connected at its lower end to the shell and at its upper end to the tubing string, a passage through the head member communicating at its upper end with the tubing string, said shell being connected to the tubing string at its lower end, a valve in the shell, said valve being loaded to move to the closed position, a tubular mandrel extending into the shell from the lower end of the passage in the head member and holding the valve in the open position, means urging the mandrel to a position remote from the valve, an explosive charge adjacent the mandrel, and an initiator for setting off the explosive charge whereby the mandrel is severed and moved from engagement with the valve.

2. A shutoff device adapted to be arranged in the tubing string of a well comprising a shell, a head member connected at its lower end to the shell and at its upper end to the tubing string, a passage through the head member communicating at its upper end with the tubing string, a series of rings within the shell, a tubular mandrel extending from the lower end of the passage in the head member through the openings of the rings, flapper valves mounted adjacent the rings adapted to close the central openings of the rings, said tubular mandrel positioned to hold the flapper valves in the open position, a compressed spring urging the tubular mandrel downward into the shell, an explosive charge adjacent the mandrel, and an initiator for setting off the explosive charge to sever the tubular mandrel.

3. A shutoff device adapted for arrangement in the tubing string of a well comprising a shell member connected at its upper end and lower end to the tubing string, a tubular mandrel supported at its upper end and extending downwardly through the shell member, a ring surrounding the tubular mandrel and engaging the inner walls of the tubular member, a valve element loaded to move to the closed position to cover the opening in the ring, said tubular mandrel holding the valve element in the open position, a well extending upwardly from the bottom of the tubular member to receive the lower end of the tubular mandrel, a compressed spring urging the tubular mandrel downward in the tubular member, an explosive adjacent the tubular mandrel, and an initiator for setting off the explosive charge to sever the mandrel whereby the mandrel is moved from engagement with the valve elements downwardly into the well.

4. Apparatus for shutting down production from a dual zone well adapted for arrangement in the tubing string of a dual zone well having a casing surrounding and spaced from the tubing string and in which production from the upper zone is conducted through the annular space between the tubing string and casing and production from the lower zone is conducted through the tubing string, comprising a shell, a head member connected at its upper end to the tubing string and at its lower end to the upper end of the shell, a packer engaging the head member and casing to prevent flow therebetween, a housing connected at its upper end to the lower end of the shell and at its lower end to the tubing string, a packing gland between the housing and shell, a passage through the head member communicating at its upper end with the tubing string, a duct through the head member communicating at its upper end with the annular space between the tubing string and casing, a valve element in the shell above the packing gland, means urging the valve element to the closed position, said valve elements being held in the open position by the mandrel, said perforations and duct being in communication when the valve element is in the open position, means urging the mandrel downward, an explosive charge adjacent to the mandrel and an initiator for setting off the explosive charge to sever the mandrel whereby it is moved from engagement with the valve element.

5. A shutoff device adapted for arrangement in the tubing string of a dual zone well having a tubing string and a casing in which production from the upper zone passes through the annular space between the tubing and the casing, said shutoff device comprising a shell connected at its lower end to the tubing string, a head member connected at its upper end to the tubing string and at its lower end to the shell whereby the shell and head member form a part of the tubing string, a packer engaging the head member and the casing preventing flow

of fluid therebetween, a passage through the head member communicating at its upper end with the tubing string, a duct through the head member communicating at its upper end with the annular space between the tubing string and casing, a packing gland positioned within the shell dividing it into an upper section and a lower section, a tubular mandrel suspended from the head member communicating with the passage and extending through the packing gland into the lower section, said lower section being connected to and opening into the tubing string below the shutoff device, perforations in the shell member above the packing gland to permit flow from the annular space into the shell member, a ring engaging the inner surface of the shell member above the perforations and having an opening through which the tubular mandrel passes, said opening in the ring being larger than the outer diameter of the mandrel to permit flow through the perforation to the duct, a valve element mounted adjacent the ring adapted to close the opening of the ring, means urging the valve element to the closed position, said mandrel normally engaging the valve element to hold it in the open position, resilient means engaging the mandrel and urging it to a position out of engagement with the valve element, an explosive charge adjacent to the mandrel between the head member and the ring, and means for setting off the explosive charge.

6. A shutoff device adapted for arrangement in the tubing string of a dual zone well having a tubing string and a casing in which production from the upper zone passes through the annular space between the tubing and the casing, said shutoff device comprising a shell connected at its lower end to the tubing string, a head member connected at its upper end to the tubing string and its lower end to the shell whereby the shell and head member form a part of the tubing string, a packer engaging the head member and the casing preventing flow of fluid therebetween, a passage through the head member communicating at its upper end with the tubing string, a duct through the head member communicating at its upper end with the annular space between the tubing string and casing, a packing gland positioned within the shell dividing it into an upper section and a lower section, a tubular mandrel suspended from the head member communicating with the passage and extending through the packing gland into the lower section, said lower section being connected to and opening into the tubing string below the shutoff device, perforations in the shell member above the packing gland to permit flow from the annular space into the shell member, a first ring engaging the inner surface of the shell member above the perforations and having an opening through which the tubular mandrel passes, a second ring engaging the inner surface of the shell below the perforations and having an opening through which the tubular mandrel passes, said openings in the rings being larger than the outer diameter of the mandrel to permit flow through the perforation to the duct, a valve element mounted at each of the rings adapted to close the opening of the rings, means urging the valve elements to the closed position, said mandrel engaging the valve elements to hold it in the open position, resilient means engaging the mandrel and urging it to a position out of engagement with the valve element, an explosive charge adjacent to the mandrel between the head member and the first ring, and means for setting off the explosive charge.

7. A shutoff device adapted for arrangement in the tubing string of a dual zone well having a tubing string and a casing in which production from the upper zone passes through the annular space between the tubing and the casing, said shutoff device comprising a shell connected at its lower end to the tubing string, a head member connected at its upper end to the tubing string and at its lower end to the shell whereby the shell and

head member form a part of the tubing string, a packing engaging the head member and the casing preventing flow of fluid therebetween, a passage through the head member communicating at its upper end with the tubing string, a duct through the head member communicating at its upper end with the annular space between the tubing string and casing, a packing gland positioned within the shell dividing it into an upper section and a lower section, a tubular mandrel secured at its upper end to the head member and extending through the packing gland into the lower section, the opening in the tubular mandrel communicating with the passage in the head member, said lower section being connected to and opening into the tubing string below the shutoff device, perforations in the shell member above the packing gland to permit flow from the annular space into the shell member, a first ring engaging the inner surface of the shell member above the perforations and having an opening through which the tubular mandrel passes, a second ring engaging the inner surface of the shell below the perforations and having an opening through which the tubular mandrel passes, a third ring engaging the inner surface of the shell below the perforations and having an opening through which the tubular mandrel passes, said openings in the rings being larger than the outer diameter of the mandrel to permit flow through the perforation to the duct, first and second valve elements mounted on the lower surface of said first and second rings, means urging said first and second valve elements upwardly to a closed position against the lower surface of the rings, a third valve element mounted on the upper surface of the third ring, means urging the third valve element downwardly against the upper surface of the third ring to close the opening therein, said mandrel engaging the valve elements to hold them in an open position, resilient means engaging the mandrel and urging it to a position out of engagement with the valve elements, an explosive charge adjacent to the mandrel between the head member and the first ring, and means for setting off the explosive charge to sever the mandrel whereby the mandrel is moved out of engagement with the valve elements to permit the valve elements to move to the closed position.

8. A shutoff device adapted to be arranged in the tubing string of a well comprising a tubular shell having its upper and lower ends connected to sections of the tubing string whereby the shell forms a part of the tubing string allowing flow therethrough, a valve element in the tubular shell, spring means urging the valve element to a closed position adapted to prevent flow through the tubing string, a valve seat within the shell positioned for engagement with the valve element when the valve element is in the closed position, means within the shell engaging the valve element to hold it in an open position during normal operation of the well, resilient means engaging said means mounted on the shell and urging said means to a position out of engagement with the valve element, an explosive charge positioned adjacent the means holding the valve element in the open position between its attachment to the shell and its engagement with the valve element and adapted to sever the means holding the valve element to allow the valve to close, and an initiator for setting off the explosive charge whereby the means engaging the valve element is severed and the valve element closes to shut off the well.

9. A shutoff device adapted to be arranged in the tubing string of a well comprising a tubular shell connected at its upper and lower ends to the tubing string to form a part of the tubing string, a valve seat within the tubular shell, a valve element in the tubular shell, resilient means engaging the valve element and urging it toward a closed position for engagement with the valve seat to prevent flow through the tubing string, a mandrel attached to the shell extending into the shell to engage

the valve element to hold it in an open position during normal operation of the well, an explosive charge adjacent the mandrel between its attachment to the shell and its engagement with the valve element, an initiator for setting off the explosive charge whereby the mandrel is severed, and resilient means engaging the mandrel adapted to move the mandrel out of engagement with the valve element after the explosive has severed said mandrel.

10. A shutoff device adapted for arrangement in the tubing string of a dual zone well having a tubing string and a casing in which production from the upper zone passes through the annular space between the tubing and the casing, said shutoff device comprising a shell connected at its lower end to the tubing string, a head member connected at its upper end to the tubing string and at its lower end to the shell whereby the shell and head member form a part of the tubing string, a packing engaging the head member and the casing preventing flow of fluid therebetween, a passage through the head member communicating at its upper end with the tubing string, a duct through the head member communicating at its upper end with the annular space between the tubing string and casing, a packing gland positioned within the shell dividing it into an upper section and a lower section, a tubular mandrel secured at its upper end to the head member and extending through the packing gland into the lower section, the opening in the tubular mandrel communicating with the passage in the head member, said lower section being connected to and opening into the tubing string below the shutoff device, perforations in the shell member above the packing gland to permit flow from the annular space into the shell member, a first ring engaging the inner surface of the shell member above the perforations and having an opening through which the tubular mandrel passes, a second ring engaging the inner surface of the shell below the perforations and having an opening through which the tubular mandrel passes, said openings in the rings being larger than the outer diameter of the mandrel to permit flow through the perforation to the duct, first and second valve elements mounted on the lower surface of said first and second rings, means urging said first and second valve elements upwardly to a closed position against the lower surface of the rings, a third valve element mounted on the upper surface of the third ring, means urging the third valve element downwardly against the upper surface of the third ring to close the opening therein, said mandrel engaging the valve elements to hold them in an open position, resilient means engaging the mandrel and urging it to a position out of engagement with the valve elements, an explosive charge adjacent to the mandrel between the head member and the first ring, and means for setting off the explosive charge to sever the mandrel whereby the mandrel is moved out of engagement with the valve elements to permit the valve elements to move to the closed position.

45 11. A shutoff device adapted to be arranged in the tubing string of a well comprising a tubular shell connected in the tubing string to form a section thereof, a valve element within the shell, a valve seat within the shell located for engagement with the valve element when the valve element is in the closed position, means urging the valve element towards the closed position in which flow through the shutoff device is prevented, a tubular mandrel within the shell connected for fluid communication with the tubing string, said mandrel being secured to the shell and extending therein to engage the valve element to hold it in an open position, an explosive charge adjacent the mandrel between its attachment to the shell and the valve element, resilient means engaging the mandrel and urging it out of engagement with the

valve element, and an initiator connected to set off the explosive charge and sever the mandrel whereby the mandrel moves out of engagement with the valve element and the valve element is moved against the valve seat to shut off the well.
